UNITED STATES PATENT OFFICE.

CHARLES JOHN ARMSTRONG, OF AUSTIN, TEXAS.

QUICK-ACTING WRENCH.

Application filed June 5, 1922. Serial No. 565,792.

To all whom it may concern:

Be it known that I, CHARLES J. ARMSTRONG, a citizen of the United States, residing at Austin, in the county of Travis and State 5 of Texas, have invented a new and useful Quick-Acting Wrench, of which the following is a specification.

This invention relates to wrenches.

The object is to provide a wrench, either 10 a nut or pipe wrench wherein, by the simple movement of an element, the movable jaw may be either locked into any desired spaced relation to the fixed jaw for operation in turning a nut, or pipe, or by a reverse movement of said element, the movable jaw may 15 be free to be adjusted to any other desired position with relation to the fixed rigid jaw.

Another object is to provide a wrench having the ordinary size and proportions, 20 the improvements adding no material weight thereto, and being wholly incorporated in the movable jaw, thus enabling the wrench to be manufactured at a low cost, and to be easily handled and quickly 25 adjusted to fit any size nut.

A further object is to provide a wrench having adjusting and holding means for the movable jaw which automatically locks into position for holding the parts, which is entirely devoid of springs, and which holds all 30 the more positively and surely when the strain is increased on the coacting jaws, as when turning a nut or bolt head, etc.

A full and complete understanding of the 35 invention may be obtained from a consideration of the following detailed description, taken in connection with the accompanying drawing forming a part of this specification; it being understood that while the drawing 40 shows a practical form of the invention, the latter is not to be confined to strict conformity with the showing thereof, but may be changed or modified so long as such changes or modifications mark no material 45 departure from the salient features of the invention, as specifically pointed out in the appended claims.

In the drawing, in which similar reference characters designate corresponding 50 parts throughout the several figures:—

Fig. 1 is a side elevation of the improved wrench, the movable jaw being locked in adjusted, spaced relation to the rigid jaw.

Fig. 2 is an elevation, partly in section, 55 the handle being broken away, and the movable jaw unlocked and free to be adjusted

to any desired position, with relation to the fixed jaw.

Fig. 3 is a front elevation of the upper portion of the wrench, the handle being 60 omitted.

Fig. 4 is a transverse sectional view, taken on the line 4—4 of Fig. 1.

In the drawing, there is illustrated a 65 wrench having a shank 1 provided, throughout the major portion of its length, with rack teeth 2, and having, at one end, a fixed jaw 3 with its overhanging end arranged on the side having the teeth, and provided, at its opposite end, with a handle 4 formed and attached to the shank in the usual manner, all of which is in accordance with the construction of ordinary wrenches of this class. 70

Mounted on the shank 1 of the wrench, and adapted to be moved longitudinally 75 thereof, is a slidable jaw 5 provided intermediate its length with a pair of arms 6 extending toward the handle and defining a space or cavity 7 therebetween. To the jaw 5 and to the outer ends of the arms 6, rearwardly-extending straps 8 are integrally connected, and are joined at their rear ends by cross bars 9 to form alined passageways 10, which receive the shank 2 and permit the movable jaw 5 to be freely moved longitudinally along the shank in either direction to bring the two coacting jaws nearer together or farther apart, as desired. 80

The distance between the outer faces of 90 the downwardly extending arms 6 is slightly less than the full width of the movable jaw 5, (Fig. 3), and the latter is hollowed out on either side in an arcuate manner, as at 11, to provide continuations flush with the surface thereof, and in like manner, the upper end of the space or cavity 7 is hollowed out or rounded up into the body of the movable jaw, as indicated at 12 in the drawing. 95

Each arm 6 is further provided in its lower portion with alined slots 13 arranged substantially along the longitudinal center lines of the arms, the lower ends of the slots being slightly below the upper edges of the straps 8, and preferably rounded at both the upper and lower ends. 100

A gear wheel 14 is located in the upper end of the space or cavity 7 and conforms to and freely turns in the rounded upper end 12 of the same, the shaft 15 of said wheel traversing suitable alined openings formed 110 in the arms 6 substantially in a line with the lower side of the movable jaw. This gear

wheel is constantly in mesh with the teeth of the rack 2 formed on the shank of the wrench, and the ends of the shaft 15 extend beyond the sides of the arms 6 by which the 5 same is carried, the said wheel being loosely mounted on the shaft and free to turn independently thereof.

A locking gear wheel 16 is slidably mounted in the lower portion of the space or 10 cavity 7, said wheel being of the same diameter as the wheel 14, and constantly in mesh with the teeth of the rack 2, the width of both wheels being such as to fill the space between the arms 6 and to freely turn or 15 slide therein. The trunnions 17 of the wheel 16 extend through the alined slots 13 and turn with the wheel, the same being free to slide upwardly or downwardly in the slots to bring the lower wheel 16 into mesh 20 with the upper wheel 14, or to disengage the same, for a purpose to be explained.

An operating yoke, preferably formed of strong, sheet metal, is adapted to be mounted on the movable jaw in a manner to engage the slidable lower wheel 16, and to force the latter into meshing relation with the upper wheel 14, or to forcibly lower the same out of engagement therewith. This yoke comprises side plates 18 spaced apart 25 a distance to receive the arms 6 therebetween, and to straddle the said arms and frictionally engage the same throughout their lengths, the upper ends of said plates being rounded to conform to the arcuate 30 cut-out portion 11 of the movable jaw, as clearly shown in Fig. 1 of the drawing. The lower ends of the plates 18, which are substantially equal in width to the width of the downwardly extending arms 6, are 35 joined by a cross plate 19 of equal width therewith, and adapted, when the sides 18 are in vertical position and parallel to the shank of the wrench, to lie close to the lower ends of said arms, there being just sufficient 40 space to allow the cross plate 19 to pass the outer corner of the same when the yoke is swung outwardly about its pivotal point on the shaft 15 at the upper end of the plates 18, as clearly shown in Fig. 2 of the drawing. 45 The bottom cross-plate 19 is extended forwardly and formed into a downwardly-turned thumb piece 20, which is used to facilitate pressing the yoke inwardly or outwardly with relation to the shank of the wrench, and the yoke is so constructed as to be readily formed from one piece of sheet metal suitably cut and bent into the shape 50 shown and described.

Intermediate the ends of the side plates 55 18 and arranged transversely thereof, are inclined cam-slots 21, the lower ends of which are located adjacent to the rear edges of the plates 18, and the upper ends close to the outer edges of the plates, and these inclined cam-slots are of sufficient width to

receive the projecting ends of the trunnions 17, which are adapted to freely slide along the inclined slots, the outer or upper ends of the latter, which are in alinement with each other, being provided with depressions 70 constituting seats 22, in which the said trunnions rest when the yoke is pressed inwardly as shown in Fig. 1. The lower cross plate 19 has its rear edge cut away, as at 75 19^a, to span the teeth of the rack 2, when the yoke is thus pressed inwardly.

When it is desired to set the jaws of the wrench in proper relative position to receive and operate on a particular size of nut or bolt head, the thumb piece 20 is grasped and the yoke swung outwardly. In doing so, the inner end 22^a of the seat 22, where joining to the lower edge of the inclined slot 21, is forced past the lowest point of the trunnions, which latter then enter the downwardly extending, inclined slots and freely drop to the bottom thereof, as the yoke is swung outwardly about its pivots 15 and consequently the lower locking wheel 16 is lowered away from and out of mesh with the upper wheel 14, and the entire lower jaw, together with its component parts, may be raised or lowered along the shank of the wrench to the desired position, as will be readily understood. During this movement of the lower jaw, when the wheels are thus separated, it will be seen that the latter do not interfere with each other, but are free to revolve independently, as both wheels are at all times in meshing relation to the rack 2 of the shank, the vertical slots 13 of the arms 6 permitting the lower wheel to rise or fall, but maintaining the said wheel in meshing relation to the said rack. By pressing inwardly on the yoke to substantially aline 100 the side plates thereof with the longitudinal axis of the shank of the wrench, the trunnions 17 are forced to travel outwardly along the inclined slots 21, and are consequently forced upwardly to bring the lower wheel 16 into meshing relation with the upper wheel 14. The said trunnions are then forced over the points 22^a, which latter are closer to the axis of rotation of the yoke about its pivots 15 than the seat or 105 any portion of the lower edge of the slot, and the trunnions are snapped into the seats 22, which thus serve to automatically lock the yoke in its inward position with the two wheels meshing, and, by reason of their toothed engagement with the rack, effectively preventing any movement of the lower jaw along the said shank. Any strain brought to bear on the jaws, when 110 thus locked, to tend to cause an opening or a separation of the same, will exert a pressure on the two wheels in the same rotary direction, thus, at their meshing point, the wheels 115 would be endeavoring to move in opposite directions which is impossible by reason of 120 125 130

their toothed engagement, as will be readily understood.

From the foregoing it will be seen that a simple, cheaply manufactured and easily operated wrench has been provided, having no complicated parts to get out of order, and that the improvements may be installed on wrenches of ordinary construction without very material changes therein, and 10 without adding any considerable weight to the same, the yoke and the wheels being the only additional parts. Any strain to which the jaws are subjected only serves to cause the trunnions of the lower, or locking wheel, to hold all the tighter in the 15 arcuate seats 22, and to prevent the separation of said wheels, or any outward movement of the yoke, and it is necessary to manually swing the latter before said 20 wheels may be separated and the lower jaw moved.

What is claimed is:—

1. A wrench comprising a shank provided with a rack, a fixed jaw at one end 25 of the shank, a handle at the other end, a movable jaw on the shank, a pair of toothed wheels in engagement with the rack and having trunnions supported by the movable jaw, a yoke pivoted on the 30 trunnions of one of the wheels, and having slots receiving the trunnions of the other wheel, the slots being inclined and serving in conjunction with said other wheel to lock the yoke in its closed position.

2. In a wrench, the combination with a toothed shank having a fixed jaw at one end and a handle at the other, of a slidably 35 jaw on the shank, a pair of gear wheels mounted in the slidable jaw and always in engagement with the teeth of the shank, a yoke straddling the slidable jaw and pivoted to the same, said yoke having inclined 40 slots, and one of the wheels having trunnions riding in the slots whereby to move 45 the last-mentioned wheel into and out of engagement with the other wheel when the yoke is rocked about its pivot.

3. A wrench having a shank provided with a rack, a fixed jaw and a handle, a 50 movable jaw mounted to slide on the shank and carrying longitudinally-alined gear wheels in mesh with the rack, said wheels having trunnions supported by the movable jaw one wheel being movable toward 55 or from the other wheel, and a yoke pivotally mounted on the slidable jaw and having inclined cam-slots for receiving the trunnions of the movable gear wheel to move the latter into or out of meshing engagement with the other wheel, when the 60 said yoke is swung about its pivot.

4. A wrench having a shank provided with a rack along one side and carrying a rigid jaw, a longitudinally-slidable jaw

having a passageway receiving the shank and 65 having a cavity communicating with the passageway for the shank, a gear wheel in the cavity meshing with the rack and having trunnions journaled in the side walls defining the cavity, said side walls also being provided with alined, longitudinally-disposed slots, a longitudinally-movable gear wheel also meshing with the rack and having trunnions extending through the 70 said slots, a yoke straddling the movable jaw and pivoted to the trunnions of the first-named gear wheel, the sides of the yoke having alined, inclined slots in which the extended trunnions of the movable gear wheel are adapted to move, the ends of the 75 slots remote from the shank being nearer to the pivots of the yoke than the other ends and there terminating in depressions constituting seats for the trunnions when the 80 yoke is swung parallel with the shank.

5. A wrench including a shank having a rigid jaw and a longitudinal rack, a co-acting movable jaw slidably mounted on the shank and provided with a longitudinally-disposed cavity, a gear wheel having trunnions mounted for rotation in the 90 side walls of the cavity near the end thereof and meshing with the rack, the walls of the cavity having longitudinal, alined slots near the end remote from said wheel, a yoke having spaced sides pivotally mounted at their free ends to the trunnions of the 95 wheel and straddling the sides of the movable jaw, said spaced sides of the yoke being joined at their other ends by a cross 100 plate adapted to lie close to the end of the movable jaw remote from the rigid jaw when the yoke is swung into parallelism with the shank, said cross plate carrying a thumb-piece on the edge opposite the shank, said sides of the yoke having inclined cam slots, the outer ends of the slots remote from the shank being closer to the 105 yoke pivots than the inner ends and having depressions at the outer terminals 110 adapted to register with the longitudinal slots of the movable jaw when the yoke is pressed inwardly against the shank, and a movable gear wheel mounted in the cavity and meshing with the rack, and having 115 trunnions traversing the opposite pairs of alined slots whereby, when the yoke is swung inwardly, the wheels are caused to mesh with each other and the trunnions to rest in said depressions to lock the movable jaw against movement, and when the yoke is swung outwardly the wheels are separated to permit movement of said 120 movable jaw.

In testimony that I claim the foregoing as my own, I have hereto affixed my signature.

CHARLES JOHN ARMSTRONG.
